UNITED STATES PATENT OFFICE.

JOHN JEPSON, OF WEST MERIDEN, CONNECTICUT, ASSIGNOR TO THE MERIDEN BRITANNIA COMPANY, OF SAME PLACE.

DESIGN FOR PICKLE-JARS.

Specification forming part of Design No. 5,371, dated November 21, 1871

To all whom it may concern:

Be it known that I, JOHN JEPSON, of West Meriden, in the county of New Haven and State of Connecticut, have invented a new Design for Pickle-Jars; and I do hereby declare the following, when taken in connection with the accompanying drawing and the letters of reference marked thereon, to be a full, clear, and exact description of the same, and which said drawing constitutes part of this specification, and represents in—

Figure 1 a side view; Fig. 2, a side view of the cover; and in Fig. 3 a side view of the jar detached.

This invention relates to a design for jars, such as are used in articles of table service, and known to the trade as pickle-casters; and consists in the design for the jar shown in the accompanying illustrations, and as hereinafter described.

The jar A is four-sided, contracting regularly from the bottom up to the top. At the bottom the jar may be contracted, as shown in the drawing, so as to form a shoulder upon which the jar may rest; but this is not essential, and is made no part of the design. The cover B projects over the sides of the jar, forming a cap, as seen in the drawing, and provided with any desirable ornament corresponding to the caster, to serve as a handle for the removal of the cover.

I claim as my invention—

The design for pickle-jar, as shown in the accompanying illustrations, and as herein described.

J. JEPSON.
